Primary Examiner — Jennifer Rivard*Assistant Examiner* — Jennylou M Binas(74) *Attorney, Agent, or Firm* — Novoclaims Patent Services LLC; Mei Lin Wong(57) **CLAIM**

The ornamental design for a glass rinser, as shown and described.

DESCRIPTION

FIG. 1 is a top perspective view of a glass rinser showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the glass rinser that form no part of the claimed design.
